CLAIM

I claim the ornamental design for a fence panel, as shown and described.

DESCRIPTION

FIG. 1 is a perspective view thereof;

FIG. 2 is a front view thereof;

FIG. 3 is a rear view thereof;

FIG. 4 is a right side view thereof;

FIG. 5 is a left side view thereof;

FIG. 6 is an upper end view thereof; and,

FIG. 7 is a lower end view thereof.

The drawings depict the design of a fence panel, and no limitations on length or size are intended thereby.
